UNITED STATES PATENT OFFICE.

ALFRED STANGE, OF COSWIG, GERMANY.

TOY FOR CHILDREN.

No. 902,771.

Specification of Letters Patent.

Patented Nov. 3, 1908.

Application filed July 2, 1907. Serial No. 381,856.

To all whom it may concern:

Be it known that I, ALFRED STANGE, a subject of the German Emperor, and resident of No. 45 Dresdenerstrasse, Coswig, 5 Germany, have invented certain new and useful Improvements in a Toy for Children, of which the following is a specification.

The object of the present invention relates to a toy for children and consists of 10 a gun, its novelty being, that series of shots in form of peas or the like, can be discharged by turning a crank, whereby a mechanism loads the gun automatically.

The accompanying drawing shows a form 15 of construction of the invention.

Figure 1 gives a side-view of the toy connected with an ammunition box. Fig. 2 is a section of the mechanism, Fig. 3 represents a longitudinal section through the 20 same. Fig. 4 is a cross section of the gun closed by the piece *g*. Fig. 5 is a cross section of the gun, the piece *g* pulled out. Fig. 6 is a side view of the piece *g*.

The mechanism of the gun consists of the 25 gun barrel *a* having a funnel-pass *b* which serves as a magazine for the loading. Underneath the funnel a short tube *c* for feeding the projectiles to the gun is arranged. In the interior of the barrel a piston *d* is 30 arranged, which is connected with a drawing-rod *e* to which a slide *f* is fastened.

On the upper side of the barrel a slit is arranged near the tube *c* which serves for the reception of the tappet of the catch-piece *g*, which possesses a weak spring *h*, which causes the automatic closing of the piece *g*. In the interior of the casing *p*, situated upon the barrel, springs *i* are arranged which are connected with the rod *e* 40 by a pin *k*. A crank *m* is supported in said casing. The drawing rod *e* is guided in a slit in said casing. Above the slit the catch *o* is movably arranged.

The manner of operating of the device is 45 as follows: The parts occupying the position shown in Fig. 2, if the magazine *b* is filled with peas or the like, one of the balls enters the tube *c* and falls on the piston *d*. By turning the crank *m* to the rear 50 the curved position of said crank within the casing *p* enters the forward notch of the rod *e*, and the latter carrying the plunger *d* is forced to the rear against the

action of the springs *i* until the slide bar *o* enters the notch *e*¹ of the said rod. In this 55 position the gun is cocked. During the travel of the plunger *d* to the rear the projectile resting thereon falls into the barrel *a*, and the slide *f* carried by the rod *e* closes the tube *c*, thereby preventing further balls 60 entering the said tube *c*. The tappet piece *g* is normally held by the slide *f* in the position shown in Fig. 2 with the weak spring *h* tensioned. During the cocking action, when said slide *f* is moved to the rear to close the 65 slot in tube *c*, the tappet piece *g* acting under the influence of its spring *h* falls into the barrel, as clearly shown in Fig. 4, thus preventing any tendency of the projectile to roll out. When the parts are in the 70 cocked position, as described, a further turn of the crank *m* to the rear causes it to leave the forward notch of the bar *e* and engage with the slide bar *o*, raising the latter from engagement in the notch *e*¹. The bar *e* 75 carrying the plunger *d* and slide *f* now acting under the influence of the tensioned spring *h*, moves forward. The slide *f* contacts with the upper part of the tappet piece *g* and raises it from the blocking position 80 shown in Fig. 4 to that illustrated in Figs. 2 and 5. The plunger *d* strikes the projectile and the latter is discharged.

I claim:

In a toy for children the combination of 85 a gun having a barrel provided with a slit, a casing on this gun; a funnel in this casing, a short tube situated underneath said funnel, a piston in the said barrel, a drawing-rod having notches and connected with the 90 said piston, a slide attached to the said rod, a catch-piece having a tappet adapted to enter into the above-mentioned slit of the barrel, a spring attached to the said catch-piece, springs situated in the said casing 95 and fastened to the above-mentioned drawing rod, a crank supported in the said casing adapted to move the rod, a turnable bar in the casing adapted to enter into one of the said notches for preventing reloading 100 the gun before a discharge, substantially as and for the purposes set forth.

ALFRED STANGE.
